UNITED STATES PATENT OFFICE.

RICHARD F. McGOWAN, OF COLUMBUS, OHIO.

FURNACE.

1,243,959.

Specification of Letters Patent. Patented Oct. 23, 1917.

Application filed January 29, 1917. Serial No. 145,064.

To all whom it may concern:

Be it known that I, RICHARD F. McGOWAN, a citizen of the United States, residing at Columbus, in the county of Franklin and State of Ohio, have invented certain new and useful Improvements in Furnaces, of which the following is a specification.

This invention relates to furnaces particularly adaptable for use in connection with power plants employing steam boilers. It is the object of this invention to provide a structure wherein smokeless combustion of the coal may be had. In accomplishing this, not only is the smoke nuisance eliminated, but also all of the heat units resulting from the combustion of the coal are utilized.

My invention, therefore, resides essentially in the provision of a unitary construction of furnace, wherein the refractory parts are heated to an incandescence more or less and these parts placed in the path of movement of the outgoing products of combustion so that the necessary heat is supplied to complete the combustion of all the coal. It is readily recognized that the volatile carbon products of coal may be expelled much more readily than the fixed carbon products and also that these volatile products are driven off very rapidly. If these are then brought into contact with highly heated surfaces, the likelihood of complete combustion is materially increased.

The preferred embodiment of my invention is shown in the accompanying sheet of drawings, in which similar characters of reference designate corresponding parts, and in which:

Figure 1 is a vertical longitudinal section showing my furnace applied to a return tubular type of boiler, as designated by line 1—1 of Fig. 2, and,

Fig. 2 is a transverse vertical section taken on line 2—2 of Fig. 1.

In these drawings, the boiler is horizontally disposed and is designated by the reference numeral 1, heat being supplied to this boiler through the combustion of the fuel upon the grate bars 2. It will be noted that these grate bars occupy a small portion of the length of the boiler and are set in position to be on a slight incline. Located directly above these grate bars is an arch structure 3 preferably made of refractory material and consisting of a series of steps 4, 5, 6 and 7. Each of these steps gradually increases in thickness so that each

succeeding step projects to a level slightly beneath the next preceding. This acts somewhat as a buffer for the outgoing products of combustion to slightly impede their progress without necessarily too greatly checking the draft. This action heats the arch to a great extent and further, because of the stepped nature of this arch, a greater surface is exposed than if its under surface were smooth. To the rear of the grate and to the rear of the arch 3, there is located a second arch 8, which is also constructed of the same material of which the arch 3 is formed and this arch 8 also projects downwardly into the path of the outgoing products of combustion, therefore, slightly deflecting their movement and also absorbing a portion of their heat. Located beneath and between these two arches is a bridge wall 9, whose lower portion is of the ordinary construction and is also made of refractory material. However, this bridge wall is capped by a checker-work structure 10, which I have shown as being formed of a plurality of brick placed one upon another in such manner that a plurality of openings is formed between them. In other words, the bricks of each layer are slightly spaced from each other to provide openings through which a portion of the outgoing products of combustion may pass. This arrangement produces a very great area for absorbing the heat under certain conditions and for emitting this heat under other conditions such as when the volatile products are being rapidly liberated.

From the foregoing description, it will be apparent that after the two arch structures and the bridge wall cap are highly heated, the rapid liberation of the volatile carbons will be correspondingly heated in their outward passage and in this manner will effect their combustion to such extent as to prevent the escape of smoke. The heat used up to effect this combustion is then replaced to a much higher degree by the combustion of the products which come into contact with these refractory structures. It will, therefore, be apparent that a very great heat radiating surface has been presented aside from the natural heat of the fuel bed and if the necessary quantity of air is then supplied, perfect combustion may be had. After passing the bridge wall 8, the products return through the boiler tubes 11 and pass out to the stack 12 in the usual manner.

What I claim, is:

1. In a furnace, a grate, a bridge wall to the rear of said grate, an open checkerwork cap on said wall made of refractory material and through the openings of which the products of combustion may pass, a refractory arch above said grate formed of a series of steps, each succeeding rearward step projecting beneath the level of the preceding, and a second refractory arch located to the rear of said bridge wall.
2. In a furnace, a rearwardly and downwardly inclined grate, a bridge wall immediately to the rear of said grate, an open

checkerwork cap on said wall made of refractory material and through the openings of which the products of combustion may pass, a refractory arch above said grate formed of a series of steps, each succeeding rearward step projecting beneath the level of the preceding, and a second refractory arch located at the rear of said bridge wall.

In testimony whereof I affix my signature in presence of two witnesses.

RICHARD F. McGOWAN.
